BUTTER DISH

Mel Appel, 9 Nottingham Road, Livingston, N.J. 07039,
and Martin Schnur, 220 St. Cloud Ave., West Orange, N.J. 07052

Original design application Nov. 2, 1966, Ser. No. 4,513.
Divided and this application July 24, 1967, Ser. No.
8,199

Term of patent 14 years

(Cl. D44—5)

FIG. 1

FIG. 2

This is a division of our co-pending application, Ser. No. D.4,513, filed Nov. 2, 1966.

We claim:

The ornamental design for a butter dish, as shown.
